UNITED STATES PATENT OFFICE.

WILLIAM LAWRENCE VARNER, OF PRATT CITY, ALABAMA, ASSIGNOR OF ONE-HALF
TO DOCTOR F. CLEVELAND, OF PRATT CITY, ALABAMA.

METAL TIE.

Application filed June 27, 1922. Serial No. 571,145.

To all whom it may concern:

Be it known that I, WILLIAM L. VARNER, a citizen of the United States, and resident of Pratt City, in the county of Jefferson 5 and State of Alabama, have invented certain new and useful Improvements in Metal Ties, of which the following is a specification.

My invention is a combined tie and rail 10 fastener, and it consists in the combinations, constructions and arrangements herein described and claimed.

An object of my invention is to provide a 15 simple and effective means for supporting a pair of rails in parallel relation and for securely holding the rails to gauge and against spreading.

A further object is to provide a device 20 of the character described which affords means for holding the rails in such manner as to permit longitudinal movement of the rails, if required, without allowing any lateral movement of the rails or an overturning or rotation of the rails about their 25 respective longitudinal axes.

A further object is to provide a device of 30 the character described which includes means for supporting spaced parallel rails and for detachably securing the rails to the supporting means without the use of bolts, spikes or like fastening elements.

A still further object of my invention is 35 to provide a device of the character described which is strong and durable and is not likely to get out of order easily in service.

Other objects and advantages will be apparent from the following description and the novel features of the invention will be 40 particularly outlined in the appended claims.

My invention is illustrated in the accompanying drawings, forming a part of this application, in which—

45 Figure 1 is a perspective view showing a pair of rails applied to a device embodying the invention.

Figure 2 is a top plan view, showing a tie in the device together with a portion of 50 the rail superimposed thereon and held by one of the rail fastening means associated with the tie, the other of the rail fastening means associated with the tie being shown in position to permit the placing of a sec-

ond rail upon the tie in a desired position 55 in respect to the first rail.

Figure 3 is a longitudinal section through the structure exhibited in Figure 2,

Figure 4 is a group perspective view of 60 a pair of rail fastening elements comprised in the device, the respective elements being shown with the rail engaging portions thereof in position to permit of the base flange of a rail being positioned therebetween.

65 Figure 5 is a section along the line 5—5 of Figure 3, and

Figure 6 is a slightly enlarged fragmentary perspective view, showing a rail supporting portion of a channel member comprised in the tie exhibited in Figs. 1 to 3 70 inclusive and in Figure 5.

In carrying out my invention, I provide 75 a tie or sleeper 1 which comprises a longitudinal member 2 rectangular in cross section and preferably made of wood. The member or tie section 2 is adapted to rest upon a supporting surface, such as the ground or a prepared foundation of ballast and the like, as indicated at 3, and is partially encased by a metallic member 4 which is substantially channel or U-shaped in cross sectional contour and is co-extensive in length with the member 2. The sides or flanges of the channel member 4 straddle 80 the member 2 and the web portion of the member 4 is disposed in flatwise parallel relation to the upper face of the member 2, being slightly spaced from and held above the latter by means which will be described 85 hereinafter.

The web of the channel member 4 includes 90 relatively depressed portions 5—5 which extend transversely thereof in spaced relation and lie in a plane parallel with the 95 face of the web and below the level of the latter. The depressed portions 5 may be formed by making kerfs across the web portion and downwardly a slight distance into the flanges of the channel member to provide a tongue which is severed at one end from one of the flanges of the channel member and is integral at its other end with the other flange of the channel member, the tongue, then being forced flatwise downwardly until the free end thereof rests upon the adjacent flange of the channel member. With this arrangement, openings extending 100

65

80

85

90

95

100

105

the width of the web are provided between the adjacent edges of the depressed portions and of the major portion or body of the web.

The depressed portions 5 serve as bridges 5 for supporting pairs of rail clips 6-6. Each rail clip or rail engaging element is substantially of inverted T-shape or in other words consists of a right angular portion having sides 7 and 8 respectively, and an 10 extension 9 which extends from the juncture of the sides 7 and 8 and lies in the plane of the side 8. The width of the extension 9 is considerably less than the length of the sides 7 and 8 and the extensions 9 are adapted to 15 be projected from above the depressed portions 5 through the openings between the side edges of the depressed portion and of the body of the web whereas the angle portion of each clip is too long to be moved 20 through such openings.

From the foregoing description of the various parts of the device, the operation thereof may be readily understood. A pair of the rail clips or rail engaging elements 6 25 are arranged in superimposed position upon each of the bridge portions 5 with the sides 8 thereof in abutting relation in respect to each other and with the ends thereof extending beyond the ends of the bridge portion 30 and thus being supported by the flanges of the channel-member as well as upon the bridge.

The extensions 9 are projected through the openings between the adjacent edges of 35 the bridge and the body of the web and extend in underlying relation to the latter as best seen in Figure 3 so that the upstanding sides 7 of the pair of rail clips extend transversely of the web in abutting relation to the 40 edges of the body of the web at opposite sides of the bridge, the ends of the upstanding side 7 and of the horizontal side 8 extending beyond the juncture of the web with the flanges thereof, as stated. It will 45 be understood that the apertures which were made in the web 4 to extend transversely thereof and to permit of the portions 5 being depressed, as described, are spaced apart so that rails 10-10 will be positioned in 50 properly spaced parallel relation when disposed upon the side portions 8 of the pair of rail clips resting upon each bridge or depressed portion 5. The rails 10-10 will be held against spreading or lateral movement 55 relatively to the channel-member when the upstanding sides 7 of the clips resting upon each bridge are bent inwardly and downwardly against the base flange of the rail at opposite sides of the latter to clamp the rail 60 to the horizontal sides 8-8 of the clips. In Figures 2 and 3, the upstanding sides of one of the pairs of rail clips exhibited therein are shown in embracing or clamping relation 65 to a rail while the upstanding sides of the other pair of rail clips illustrated are shown

in vertical position to permit of a rail being conveniently placed transversely of the channel-member to extend between the upstanding sides 7-7 and in superimposed relation to the horizontal sides 8-8.

The channel member 4 is provided with openings 11 through the web thereof adapted to engage with spikes 12 which are driven therethrough into the underlying member 2. The members 4 and 2 are thus secured together and form the tie provided by my invention. The openings 11 are preferably adjacent to the transverse apertures in which the rail clips are disposed.

The under section of the tie being made 80 of wood, shocks and jars imparted to the tie are absorbed without occasioning any undue strain or wear on the device. The lowermost section of the tie, which is of wood, is partially encased by a metallic section, 85 as described, and a tie provided by my invention is therefore more durable and stronger than a tie which is made entirely of wood, while at the same time my improved device includes a tie which is free from the 90 objectionable features of ties which are made entirely of metal. The rail fastening means cannot be moved from applied position on the tie when in rail supporting and 95 engaging position but can be readily removed from and applied to the tie when not in rail engaging position and the rails have been moved out of superimposed position.

Obviously, my invention is susceptible of 100 embodiment in forms other than that illustrated in the accompanying drawings and I therefore consider as my own all modifications of the forms of the device disclosed herein, which fairly fall within the scope 105 of the appended claims.

I claim:—

1. A device of the character described comprising a tie element made of metal and being substantially of channel-shape, the web portion thereof being horizontally disposed and uppermost, said tie element having transverse apertures formed through the web portion thereof at spaced apart points, and pairs of rail fastening elements supported within said apertures and being adapted to clampingly embrace rails, said rail fastening elements having portions extending in engagement with the underside of the web portion and holding the fastening elements against movement relatively to 110 the tie element when in embracing relation to said rails, and a wooden tie element partially encased by the channel-shaped element and providing a support for the latter.

2. A device of the character described 115 comprising a tie element made of metal and being substantially of channel-shape, the web portion thereof being horizontally disposed and uppermost, said tie element having transverse apertures formed through the 120

130

- web portion thereof at spaced apart points, and pairs of rail fastening elements supported within said apertures and being adapted to clampingly embrace rails, said 5 rail fastening elements having portions extending in engagement with the underside of the web portion and holding the fastening elements against movement relatively to the tie element when in embracing relation 10 to said rails, a wooden tie element partially encased by the channel-shaped element and providing a support for the latter, and means securing the metallic tie element to the underlying wooden tie element.
- 15 3. In a device of the character described, a tie element consisting of a longitudinal metallic channel member having an aperture extending transversely through the web portion of the channel member, and a pair 20 of rail engaging elements having portions extending in underlying contiguous relation to the web of the channel member from opposite edges of the aperture and having other portions extending upwardly through 25 the aperture at opposite sides of a rail superimposed thereon, said last-named portions of the fastening element being adapted to be bent into embracing relation to the base flange of the rail and said first portions of 30 the rail fastening elements being adapted to engage the web portion of the channel member to prevent movement of the rail fastening elements relatively to the channel member when the upper portions thereof are in 35 engagement with the rail.
4. In a device of the character described, a tie element, consisting of a metallic channel shaped member, said channel member having a transverse portion of the web there- 40 of relatively depressed, thereby defining an aperture in the web and a bridge extending
- between the flanges of the channel member, and a pair of rail engaging elements, each rail engaging element being of inverted T-shape and having a portion thereof superimposed upon the bridge and extending at its ends laterally of the channel member, and another portion extending between the adjacent edges of the bridge and the body of the web in underlying relation to the latter and an upstanding portion projecting above the plane of the body of the web adjacent to one edge of the aperture, the upstanding portions of a pair of rail fastening elements being adapted to straddle the 50 base flange of the rail and to be bent inwardly and downwardly into embracing relation thereto, whereby the pair of rail fastening elements will be held against movement relatively to the channel-member 55 and the rail also will be held against lateral movement relatively to the channel-member.
5. In a device of the character described, a tie element of inverted channel-shape, said tie element having a portion relatively depressed in respect to the plane of the web thereof and extending transversely of the tie element, said depressed portion being severed at its side edges from the remainder of the web of the tie element, and rail fastening elements resting upon the depressed portion and adapted to have a rail superimposed thereon, said rail fastening elements having portions extending into engagement with the under sides of the portions of the 70 web at opposite sides of the depressed portion and having other portions extending upwardly above the plane of said web and being adapted for engagement with the rail at opposite sides of the latter, as and for 75 the purpose set forth.

WILLIAM LAWRENCE VARNER.
